APPARATUS FOR APPLYING PAINT

Alexander F. Jenkins, Baltimore, Md.

Application February 18, 1931, Serial No. 516,798

16 Claims. (Cl. 299—140.1)

This invention relates to spray guns for paint or similar coating material and more particularly to the type of spray gun, or so-called air brush, in which auxiliary jets of compressed air are employed to alter the shape of the spray of coating material impelled by the main air blast.

The general object of the invention is the provision of a novel and improved spray gun which is capable of more accurate operation than the usual device of this type and one in which the air supply to both the impelling and the modifying jets may be readily controlled.

Another object of the invention is to provide a spray gun of this type which embodies certain features of construction by which the ease and economy of manufacture are appreciably increased.

One feature of the invention, whereby greater accuracy and evenness of outline of the spray of coating material is obtained, is the improved construction of the nozzle of the spray gun, particularly with reference to the manner of drilling and forming the portions thereof through which issue the supplemental jets.

Another highly important feature of the invention is the provision of a novel air controlling valve by means of which the supply of air may not only be cut off entirely from both the main and supplemental jets but the quantity or pressure of the initial air supplied to the valve chamber and of that issuing from said chamber to both jets may be varied at will.

Other objects and features of novelty will be apparent from the following specification when read in connection with the accompanying drawings in which one embodiment of the invention is illustrated by way of example.

In the drawings:

Figure 1 is a side elevational view, partly in vertical longitudinal section, of a spray gun or air brush forming one embodiment of my invention;

Figure 2 is a view in rear elevation of a portion of the nozzle of the spray gun;

Figure 3 is a transverse sectional view taken on line 3—3 of Figure 1;

Figure 4 is a fragmentary top plan view of the rear body portion of the spray gun;

Figure 5 is a transverse cross sectional view taken on line 5—5 of Figure 1;

Figure 6 is a view in side elevation of the body portion of the air valve;

Figures 7, 8, and 9 are transverse sectional views thereof taken on lines 7—7, 8—8, and 9—9, respectively, of Figure 6;

Figure 10 is a diagram illustrating the operation of the air valve;

Figure 11 is a view similar to Figure 1, showing the body portion of another form of my improved spray gun; and

Figure 12 is a fragmentary sectional view taken on line 12—12 of Figure 11.

The spray gun designated generally by the numeral 10 in Figure 1 comprises the forward body portion 11, which is adapted to carry the spray nozzle and its associated parts, the rear body portion 12, which is adapted to house the air controlling valve and the operating mechanism for the coating material valve, the upper connecting portion 13 through which the air passages to the nozzle are adapted to pass, and the lower connecting portion 14. Any suitably designed handle or grip 15 may be provided, and the ring or eye 16 is formed upon the upper portion of the spray gun for the purpose of providing means whereby the gun may be suspended from a suitable support when not in use.

At the lowermost point of the forward body portion 11 there is provided the boss 20 which is interiorly threaded as at 21 for the attachment of suitable connections leading to the supply of paint or other coating material. From this boss the passageway 22 leads to the central coating material chamber 23 into the open forward end of which is threaded the coating material nozzle member 25. The forwardly projecting portion of the nozzle member 25 is generally conical in shape and this member is provided with the bore 26 which is tapered to form the restricted forward orifice 27. As a means for controlling the flow of coating fluid through the orifice 27 the tapered needle valve 28 is provided and is adapted to reciprocate longitudinally within the central bore of the member 25 and to be carried by the valve stem 29 which projects rearwardly from the forward body portion 11 of the gun through the bore 30, packing 31, and packing nut 32. The valve stem 29 is actuated by means disposed within the rear body portion 12 which will be later described.

The coating material nozzle member 25 is provided with the radially extending flange 35 which is adapted to overlie the front face of the body portion 11 and is provided with a circular series of spaced perforations 36 which are connected at their rearwardly disposed ends by the annular groove 37 which is adapted to provide communication between these orifices 36 and the compressed air passageway 40 which passes through the upper connecting portion 13 of the spray gun.

gun. By this means the main air supply for impelling the paint spray is conducted to the chamber 41 formed within the nozzle head 42. The nozzle head 42 is adapted to surround the paint supply nozzle 25 and is adapted to fit snugly around the outer periphery of the flange 35.

Centrally of the forward wall of the nozzle head 42 there is provided an aperture 45 which surrounds the restricted forward end of the paint nozzle member 25 so as to provide an annular opening 46 through which the main air jet is adapted to flow so as to draw the paint supply through the orifice 27 when the needle valve 28 is opened. The nozzle head 42 is retained in position by means of the lock nut or collar 48 which is adapted to be threaded upon the forward body portion 11 as at 49. The collar 48 is adapted to enclose the outer annular air chamber 50 which is adapted to receive a supply of air from the passageway 51 for the operation of the supplemental air jets which serve to flatten the spray of coating material which issues from the main jet 27, 46.

Upon the forward end of the nozzle head 42 there are formed the diametrically oppositely disposed raised portions or projections 53 which are provided with the inner converging faces 54. Within the confines of the collar member 48, the head 42 is provided with the annular surface 55 which is parallel with the surfaces 54 formed on the projections 53. Each of the projections 53 is provided with the passageways 56 which are drilled through the projections so that their axes are respectively perpendicular to the surfaces 54 and 55. It will be readily understood that the auxiliary air supply from the chamber 50 will be directed through the converging passageways 56 and will impinge upon the circular spray provided by the central jet orifice 27, 46 and serve to flatten the jet of sprayed material in the manner desired for certain kinds of work. The provision of parallel surfaces connected by the perpendicular passageways 56 is an important feature of the present invention. This feature not only assists in facilitating the operation of drilling, but also provides a passageway, the length of all sides of which are equal. This eliminates the presence of a greater degree of friction to which the air would be subjected in passing along the longer side of the passage and the consequent unevenness of the jet issuing from the supplemental passageway.

The nozzle head 42 is provided with the radial flange 60, the outer periphery of which is adapted to contact the inner surface of the collar 48 as at 61. This flange 60 is provided with the holes 62 at spaced intervals around its periphery for the passage of the air through the chamber 50. The inner end of the nozzle head 42 is provided with the radial flange 63 which is adapted to cover the annular groove 64 formed in the front face of the body member 11. The flange 63 is also provided with the holes 65 which may be disposed in the same angular relation as the holes 62 in the flange 60 as shown in Figure 2 of the drawings. Thus it will be seen that the supplemental air supply passes through the passageway 51, groove 64, holes 65 and 62, chamber 50 and passageways 56 from which it issues in the form of auxiliary air jets for flattening the spray.

The rear body portion 12 is provided with the longitudinal bore 70 wherein is rigidly secured the bushing 71. Threaded into the rear end of the bushing as at 72 is the nut 73, sockets 74 being provided therein for the reception of an

appropriate tool for applying and removing the same. The enlarged rearward portion 75 of the needle valve stem 29 is adapted to reciprocate within the central bore of the nut 73. In order to continually urge the needle valve 28 toward its forward closed position within the nozzle member 25, an abutment 76 is rigidly secured to the stem 75 and a coil spring 77 is adapted to be compressed between the abutment 76 and the forward end of the nut 73. An adjustable cylindrical abutment 78 is threaded upon the enlarged valve stem portion 75 and is provided with a flat surface 79 which is adapted to cooperate with a correspondingly flattened interior portion 80 of the bushing 71 so as to prevent rotation of the abutment 78.

The abutment 78 is adapted to be engaged by the yoke 81 which is pivoted as at 82 upon an intermediate portion of the trigger 83. A rearwardly extending lever 84 is formed upon the yoke 81 for manipulation preferably by the thumb of the operator to release the yoke 81 from its operative position wherein it is adapted to straddle the valve stem 29, 75. The trigger 83 is pivoted to an upper portion of the spray gun as at 85. In order to adjust the yoke contacting abutment 78 along the valve stem it is only necessary to rotate the stem portion 75 by manipulating the knurled handle 87 at the rearmost end thereof whereupon the threaded abutment 78 may be moved to any desired position within certain limits along the stem 75 and thereby to permit engagement by the yoke 81 at various selective points during the pivotal movement of the trigger 83.

The means for supplying the air to the main and supplemental nozzle jets will now be described. Within the upper part of the rear body portion 12 there is provided a drilled chamber 90 which is adapted to receive the three-way air valve designated generally by the numeral 91. The rear body portion 12 is provided upon one side with the boss 92 which is interiorly threaded as at 93 for the reception of a flexible conduit leading from a source of pressure fluid such as compressed air. The interior of the boss 92 communicates with the chamber or bore 90 by means of the orifice 95. Leading from the upper wall of the forward portion of the bore 90 are the passageways 96 and 97 which communicate respectively with the passageways 40 and 51 which pass through the connecting portion 13 of the body member to the nozzle. It will be understood that the passageway 96 provides communication with the main central spray nozzle and that the passageway 97 provides communication with the supplemental wing jets 56.

The valve body member or casing 91 is provided with four separate stepped portions of different diameter, the largest and rearmost portion adapted to enclose the inlet air chamber 98, the two intermediate portions adapted to enclose the outlet air chamber 99 and the smallest forward portion adapted to close the forward end of the bore 90 as at 100. The rear end of the valve casing 91 is adapted to be closed by the threaded cap 102 and the inlet chamber 98 and the outlet chamber 99 are separated by the valve seat 103, the orifice of which is adapted to be controlled by valve body member 104, preferably being in the form of a spherical stainless steel ball. Valve stem 105 is adapted to pass through the packing nut 106 at the forward end of the valve chamber and to be actuated by contact

with the yoke 107 carried by the trigger 83 to raise the valve 104 from its seat against the pressure of the coil spring 108 which is adapted to be retained by the cap 102. It will be understood that the actuation of the valve 104 will permit the air to pass from the inlet chamber 98 of the valve to the outlet chamber 99 and thence to the nozzle.

In order to control the quantity of air flowing into the inlet chamber 98 through the passageway 95 and from the outlet chamber 99 to the passageways 96 and 97, the valve body or casing 91 is rotatable within the body 90 and is provided with the apertures 110, 111, and 112, which communicate respectively with the passageways 95, 96, and 97. The valve body or casing 91 is continuously urged forwardly within the bore 90 by means of the coil spring 115 which is adapted to be compressed between the cap 102 and the nut 116 which is threaded within the rear end of the bore 90. A stem 118 rigidly secured at its forward end to the cap 102 extends rearwardly through an aperture in the closure 116 and is provided at its rear end with the knurled nut or handle 120 which is secured to the stem 118 as, for example, by means of the set screw 121. The closure nut 116 may be provided with a circular series of sockets 122 for the insertion of a suitable tool for applying and removing the nut but during operation of the gun the forwardly extending flange 123 of the handle nut 120 is adapted to entirely cover the closure nut 116 and to abut the body portion 12 as at 124. As clearly shown in Figure 4 of the drawings, the periphery of the member 120 is graduated as at 125 so that the rotated position of the valve body 91 may be known at any time by referring the graduations 125 to the arrow 126 on the body portion 12.

In order to gradually throttle or diminish the flow of air into the inlet chamber 98 and also from the outlet chamber 99 into the passageways 96 and 97, the tapering grooves 130, 131, and 132 are provided in the outer walls of the valve casing 91 so as to intersect the orifices 110, 111, 112, respectively. The arrangement of these grooves and orifices is most clearly shown in Figures 6-10 of the drawings. The diameters and the peripheral dispositions of the orifices 110, 111, and 112 are selected so that the orifice 110 will begin to register with the inlet air passageway 95 in advance of the initial registry of the orifice 111 with the passageway 96 and both of these orifices will register with their respective passageways prior to the registry of the orifice 112 with its passageway 97. The respective points at which these orifices begin to register with their respective passageways is diagrammatically illustrated in Figure 10 of the drawings which has not been drawn to scale, the sizes of the openings and other dimensions being merely exemplary and not limiting in any sense. In this figure, the transverse sections through the several grooves and orifices have been projected in linear form rather than in circumferential and the point of maximum flow through the orifice 110 has been displaced through 90° so that it coincides with the points of maximum flow through the orifices 111 and 112 and are indicated by the legend "maximum". The points of successive initial registry of the margins of the orifices with their respective passageways are indicated by the letters A, B, and C. The grooves 130, 131, and 132 are so arranged that through a rotation of approximately 270° they all diminish in depth from a maximum, (at the orifices 110, 111, 112) to a minimum as indicated in the dia-

gram of Figure 10 at which point there is still a slight flow of air into the inlet chamber 98 and a slight flow of air is permitted also to flow through the orifice 111, groove 131, to the main nozzle jet passageway 96. However, at this point of minimum flow, the groove 132 through which air is supplied to the wing jet passageway 97 disappears and the supply of air to these jets is cut off entirely. During rotation of the valve body 91 through the remaining 90° from the minimum point to the maximum, as shown in the extreme right hand portion of Figure 10, the supply of air to the wing jets is cut off and the inlet air supply and main nozzle jet supply increases from the minimum to the maximum. The line D in Figure 10 represents substantially the point at which a maximum round spray may be obtained, the supply of air to the wing jets being cut off at this point. As already indicated, any desired condition of flow to the main and wing jets may be obtained by rotating the valve body 91 by manipulating the nut 120 with reference to the position of the graduations 125 thereon. In Figure 4 of the drawings, the nut 120 is shown in its zero position, that is, in the position it occupies with reference to the arrow 126 when the ports of the three-way air valve are in full registry with the corresponding inlet and outlet passageways of the spray gun. From this initial position, the nut may be turned in a direction to obtain either a flat or a round spray. In the embodiment illustrated, the portion of the scale 125 which must register with the arrow 126 to secure a round spray is indicated by the arrow marked "R" and the scale portion indicated by the arrow 110 designated by the letter "F" must register with the arrow 126 when a flat spray is to be obtained. In other words, the rotation of the nut 120 in the clockwise direction gives a flat spray and in the counter-clockwise direction gives a round spray.

It will also be understood that when the valve is set to supply the desired flow of air, the cut-off valve 104 is opened by manipulation of the trigger 83 and then in the proper sequence determined by the adjustment of the needle valve nut 120 87, the needle valve 28 is opened, supplying coating fluid to the nozzle whereupon it is sprayed upon the work by the air jets which have preferably already come into operation.

Although the grooves have been illustrated and described as having their minimum depths at points three-quarters of the way through the cycle of adjustment of the valve, it is to be understood that these points can be located at varying distances from the apertures as desired.

In the embodiment illustrated in Figures 11 and 12 of the drawings, the body of the spray gun is formed by die-casting a suitable metal around certain machined parts and other inserts. This embodiment is of the same general shape as the form illustrated in Figure 1 comprising the forward body portion 140, the rearward body portion 141, the upper and lower connecting portions 142 and 143, and the handle or grip 144. The machined inserts referred to may comprise the forward nozzle receiving member 146 and the stepped bushing member 147 which is adapted to receive a three-way valve member similar in all respects to the valve 91 illustrated in Figure 1 of the drawings. These elements are adapted to be connected by the tubes 148 and 149 which are made of copper or other suitable material and are connected to the inserts 146 and 147 by having their forward ends brazed into the sockets 150 and 151 in the nozzle receiving member 150.

146 and by having their rear ends brazed into the apertures 152 and 153 formed in the bushing insert 147. After the inserts are thus connected, the remainder of the body portion of the spray gun is die-cast around these elements.

The forward insert member 146 is exteriorly threaded as at 155 for the reception of a nozzle retaining collar 48 which is illustrated in Figure 1. The member 146 is interiorly threaded as at 157 for the reception of the coating material nozzle member 25 and the chamber 158 is formed within the member 146 for the reception of coating material through a suitable passageway, the general location of which is indicated by the broken lines at 159 leading to the boss 160 and which may be formed in any suitable manner such as by drilling or being cored out during the casting process. A restricted bore 161 is provided in the machined part 146 for guiding the needle valve stem controlling the flow of coating material through the nozzle. A threaded chamber 162 is provided in the rearward portion of the member 146 for the reception of packing elements such as designated by the numerals 31 and 32 in Figure 1.

The interior of the bushing 147 is shaped exactly like the recess 90 provided in the spray gun 10 illustrated in Figure 1, having the four stepped portions corresponding to the similarly stepped surfaces of the valve 91 and also being provided with the inlet passageway 164 corresponding to the passageway 95 shown in Figure 1.

Through the lower part of the rearward body portion 141 there is provided the bore 166 which is adapted to receive the needle valve actuating mechanism which is similar in most respects to the mechanism already described with reference to the first embodiment of the invention. The needle valve operating mechanism in this latter case, however, differs in the following respect from the former embodiment. The bushing 71 having the flattened wall portion 79 is dispensed with and, in its stead, the rearward part of the lower connecting portion 143 is provided with the boss 168 provided with the flat upper surface 170. This boss performs the same function as the sleeve or bushing 71 in preventing the adjustable abutment 78 from rotating upon the needle valve stem 25 during adjustment thereof, by means of the cooperation of the flattened surface 80 on the abutment 78 and the surface 170 on the boss 168.

It will be understood that by means of the present invention, there has been provided a spray gun which affords a wider range of usefulness in permitting a more accurate control of atomization in delivering fluid in proportions regulated according to the needs of the operation being performed and the materials used. Also, one of the important features of the present device is that practically any source of impelling fluid may be used regardless of whether the pressure thereof exceeds that required for the particular operation to be performed, by means of a suitable construction and adjustment of the throttling valve of the gun, thus eliminating the necessity of the employment of reducing valves or regulators in these situations. It will also be perceived that the graduation of the grooves in the three-way air valve prevents an undesirable disproportion between the velocity of the air flowing to the center nozzle and that flowing to the side wing jets which serve to flatten the spray.

75 It will be understood that various changes and

modifications may be made in the embodiment illustrated and described herein without departing from the scope of the invention as defined in the following claims.

Having thus described the invention, what is claimed as new and desired to be secured by Letters Patent is:

1. In a spraying device for coating material, in combination, a body portion, a nozzle provided with a coating material orifice, an associated propelling fluid orifice, and a supplemental fluid orifice for providing a spray modifying jet, means for controlling the supply of coating material to said nozzle, and a valve for controlling the supply of pressure fluid to said nozzle comprising a casing adapted to be adjustably secured within a recess formed in said body portion, a chamber within said casing, a valve seat and associated valve body member adapted to divide said chamber into an inlet portion and an outlet portion, separate passageways leading from the pressure fluid orifices in said nozzle and opening into said recess, a passageway leading from a pressure fluid connection and opening into said recess, said casing being provided with an aperture communicating with said inlet portion of the valve chamber and registerable with said last named passageway opening, and with two apertures communicating with said outlet portion and each registerable with the opening of one of the passageways leading to the nozzle, means associated with each of said apertures for throttling the flow of fluid therethrough upon adjustment of said valve.

2. A spraying device as set forth in claim 1 in which means are provided for rotating said valve within said recess to effect said throttling of the pressure fluid.

3. A spraying device as set forth in claim 1 in which the valve casing apertures are of such size and disposition with respect to each other as to register with their cooperating passageway openings in a definite predetermined sequence.

4. A spraying device as set forth in claim 1 in which the valve casing apertures are of such size and disposition with respect to each other as to register with their cooperating passageway openings in the following order:—the inlet aperture, the outlet aperture communicating to the impelling orifice of the nozzle, and finally the outlet aperture communicating with the supplemental spray modifying jet.

5. A spraying device as set forth in claim 1 in which the throttling means of all of the apertures are adapted to proportionately reduce the flow of fluid therethrough from a maximum to a minimum during a portion of the adjusting movement of the valve and during the remaining portion of said movement the throttling means associated with said supplemental jet passageway is adapted to cut off the flow through its aperture and the other two throttling means are adapted to increase the flow of fluid through their associated apertures from a minimum to a maximum.

6. In a spraying device for coating material, in combination, a body portion, a nozzle provided with a coating material orifice, an associated propelling fluid orifice, and a supplemental fluid orifice for providing a spray modifying jet, means for controlling the supply of coating material to said nozzle, and a valve for controlling the supply of pressure fluid to said nozzle comprising a casing adapted to be adjustably secured within a recess formed in said body portion, a chamber within said casing, a valve seat and associated valve body member adapted to divide said cham-

- ber into an inlet portion and an outlet portion, 5 separate passageways leading from the pressure fluid orifices in said nozzle and opening into said recess, a passageway leading from a pressure fluid connection and opening into said recess, said casting being provided with an aperture communicating with said inlet portion of the valve chamber and registerable with said last named passageway opening, and with two apertures communicating 10 with said outlet portion and each registerable with the opening of one of the passageways leading to the nozzle, peripheral grooves formed in the outer surface of said casing, each of said grooves intersecting one of said apertures and being of a 15 graduated depth whereby the pressure and flow of fluid through said apertures and corresponding passageways may be regulated by rotative adjustment of said valve within said recess to present different portions of said grooves to said passageway openings. 20
7. A spraying device as set forth in claim 6 in which the maximum depths of said grooves occur adjacent their associated apertures and progressively and proportionately increase in depth 25 around a portion of the circumference of said valve whereupon the groove associated with the aperture adapted to communicate with the supplemental spray modifying nozzle jet ends, and the other two grooves for the remainder of the 30 circumference of said valve progressively and proportionately increase in depth.
8. In a spray gun for applying coating material or the like, a valve actuating mechanism comprising a valve stem, a trigger, and operative connections between said stem and said trigger, comprising an adjustable abutment member carried by said stem and a boss formed upon a portion of said gun adapted to cooperate with a portion of said abutment member to prevent the rotation of 40 said member especially during adjustment thereof.
9. In a spray gun for applying coating material or the like, a valve actuating mechanism comprising a valve stem, a trigger, and operative connections between said stem and said trigger, comprising an adjustable abutment member carried by said stem, and a bushing secured within said body portion and having a flattened interior wall portion, a correspondingly flattened portion on 45 said abutment member adapted to cooperate therewith to prevent the rotation of said member especially during adjustment thereof.
10. In a spraying device for coating material or the like, in combination, a nozzle provided with coating material and pressure fluid orifices, means 55 for controlling the supply of coating material to said nozzle, and a cartridge-like valve assembly for controlling the supply of pressure fluid to said nozzle, said assembly having a valve chamber therein, a valve seat and associated valve body member within said chamber adapted to divide said chamber into an inlet portion and an outlet portion, and means for bodily and adjustably rotating said valve for regulating the pressure and rate of flow of said pressure fluid to said nozzle. 60
11. In a spraying device for coating material or the like, in combination, a nozzle provided with coating material and pressure fluid orifices, means for controlling the supply of coating material to said nozzle, and a cartridge-like valve assembly 65 disposed within a seat formed in said device for controlling the supply of pressure fluid to said nozzle, said assembly having a valve chamber therein, a valve seat and associated valve body member within said chamber adapted to divide said chamber into an inlet portion and an outlet 70 portion, means for bodily adjusting said valve assembly for regulating the pressure and rate of flow of said pressure fluid, and means on said valve assembly adapted to cooperate with said valve assembly seat, whereby upon adjustment of said valve assembly seat, the pressure and flow, both into said inlet portion and from said outlet portion of said chamber, is regulated. 80
12. In a spraying device for coating material or the like, in combination, a nozzle provided with a coating material orifice, an associated propelling fluid orifice, and a supplemental fluid orifice for providing a spray modifying jet, means for controlling the supply of coating material to said nozzle, said device being provided with a recess, portions of which are respectively in communication with said propelling fluid and said modifying fluid orifices, and a cartridge-like valve assembly disposed within said recess for controlling the supply of pressure fluid to said nozzle, said assembly 90 having a valve chamber therein, a valve seat and associated valve body member within said chamber adapted to divide said chamber into an inlet portion and an outlet portion, means for adjusting said valve assembly for regulating the pressure and rate of flow of said pressure fluid, and means on said valve assembly adapted to cooperate with said valve assembly recess, whereby upon adjustment of said valve assembly the pressure and rate of flow into said inlet portion of said 100 valve chamber and from said outlet portion to both the propelling and modifying fluid orifices of the nozzle is regulated. 95
13. In a spraying device for coating material or the like, in combination, a nozzle provided with coating material and pressure fluid orifices, means for controlling the supply of coating material to said nozzle, and a valve for controlling the supply of pressure fluid to said nozzle comprising a hollow shell rotatably mounted within 110 said device through which all of the pressure fluid must pass, means for bodily and adjustably rotating said shell for the purpose of graduating the flow and pressure of said fluid, and a cut-off valve enclosed within said shell for starting and 105 stopping the entire flow of pressure fluid. 115
14. In a spraying device for coating material or the like, in combination, a nozzle provided with coating material orifices, an associated propelling fluid orifice, and a supplemental fluid orifice for providing a spray modifying jet, means for controlling the supply of coating material to said nozzle, and a valve for controlling the supply of pressure fluid to said nozzle comprising a hollow shell rotatably mounted within said device through which all pressure fluid must pass, separate connections between said fluid orifices and said shell, means on said shell cooperating with said connections, means for bodily and adjustably rotating said shell for the purpose of 120 graduating the flow and pressure of said fluid to both said propelling and modifying fluid orifices, and a cut-off valve enclosed within said shell for starting and 125 stopping the entire flow of pressure fluid. 130
15. In a spraying device for coating material or the like, in combination, a nozzle provided with coating material and pressure fluid orifices, means for controlling the supply of coating material to said nozzle, and a valve for controlling the supply of pressure fluid to said nozzle comprising a unitary valve assembly rotatably mounted within said device through which all of the pressure fluid must pass, means for bodily and adjustably rotating said assembly as a 135 140
16. In a spraying device for coating material or the like, in combination, a nozzle provided with coating material and pressure fluid orifices, means for controlling the supply of coating material to said nozzle, and a valve for controlling the supply of pressure fluid to said nozzle comprising a unitary valve assembly rotatably mounted within said device through which all of the pressure fluid must pass, means for bodily and adjustably rotating said assembly as a 145 150

unit for the purpose of graduating the flow and pressure of said fluid, and reciprocating means within said assembly for opening up and cutting off the flow of pressure fluid, and means 5 for restraining said unitary assembly against reciprocation.

16. In a spraying device for coating material or the like, in combination, a nozzle provided with coating material and pressure fluid orifices, means 10 for controlling the supply of coating material to said nozzle, and a valve for controlling the supply of pressure fluid to said nozzle comprising a unitary valve assembly rotatably mounted within

said device through which all of the pressure fluid must pass, means for bodily and adjustably rotating said assembly as a unit for the purpose of graduating the flow and pressure of said fluid, and reciprocating means within said assembly for opening up and cutting off the flow of pressure fluid, means for restraining said unitary assembly against reciprocation, a trigger, and operative connections between said trigger and said coating material supplying means and said reciprocating means. 80 85
